TOY TRAILER TRUCK

Robert H. Crowle, Mount Prospect, and William G. Crowle, Deerfield, Ill., assignors to General Box Company, Des Plaines, Ill., a corporation of Delaware

Filed Mar. 12, 1962, Ser. No. 69,188

Term of patent 14 years

(CL. D34—15)

FIGURE 1 is a perspective view of a toy trailer truck showing our design;

FIGURE 2 is a plan view of the toy trailer truck illustrated in FIGURE 1;

FIGURE 3 is a rear elevational view of the toy trailer truck illustrated in FIGURE 1;

The essential features of my design reside in a cab section having vertically extending front and sides with a horizontal roof, and an integral portion extending from the bottom having vertical sides and a flat horizontal top that is connected to an open trailer section having vertically extending rear and sides, with a horizontal shelf or seat positioned within and at the rear end of the trailer section, all as shown.

The side not shown is substantially the same as that shown, and the dominant features of our design reside in the portions shown in full lines.

We claim:

The ornamental design for a toy trailer truck, substantially as shown and described.
